DESIGN FOR A COMBINED CHANGE
PURSE AND WALLET

Jack Rosenfeld, New York, N. Y.

Application March 25, 1948, Serial No. 145,342

Term of patent 14 years

(Cl. D87—3)

To all whom it may concern:

Be it known that I, Jack Rosenfeld, a citizen of the United States of America and a resident of the city of New York, county of New York, and State of New York, have invented a new, original, and ornamental Design for a Combined Change Purse and Wallet, of which the following is a specification, reference being had to the accompanying drawing, forming a part thereof.

In the drawing:

Fig. 1 is a view in perspective of a partly opened combined change purse and wallet, showing my new design;

Fig. 2 is a view in perspective of the same, shown fully closed; and

Fig. 3 is a bottom plan view of the same when in the position of Fig. 1.

The essential features of the design reside in the portions shown in solid black lines.

I claim:

The ornamental design for a combined change

purse and wallet, substantially as shown and described.

JACK ROSENFELD.
